UNITED STATES PATENT OFFICE

2,057,057

TERMINAL CONNECTER

Albert R. Reid, Niagara Falls, N. Y., assignor to
U S L Battery Corporation, Niagara Falls, N. Y.,
a corporation of New York

Application August 27, 1928, Serial No. 302,329

1 Claim. (Cl. 173—259)

My present invention relates to a storage battery terminal connector and more particularly to the type of connector liable to corrosion from contact with acid and acid fumes.

5 A distinct disadvantage which exists in the type of terminal connector generally employed is that, when in a corroded condition, it is extremely difficult to remove or disconnect it from engagement with the battery terminal. This is principally due to the fact that the connector is held in contact with the battery terminal by a nut and bolt, or other screw-threaded means. As corrosion, caused by the acid and acid fumes which seep up from the battery cells, progresses, the nut becomes firmly frozen to the bolt and great effort

10 is required to remove it therefrom.

My invention contemplates the provision of a connector wherein the use of screw-threaded elements has been eliminated, the parts thereof being frictionally secured in their operative position, and which may be attached to and detached from both the storage battery terminal and the connector leading thereto, with a minimum of effort.

15 The principal object of the invention is to provide a battery terminal connector of extremely simple construction which may be quickly and easily connected to a storage battery terminal and the connector leading thereto, and which 20 may be readily removed therefrom when in a corroded condition.

Other objects and advantages will be apparent from the following description.

In the accompanying drawing—

25 Figure 1 is a sectional view of a connector embodying my invention, showing the same connecting a battery terminal post to a conductor.

Figure 2 is a top plan view thereof, and

30 Figures 3 and 4 are side and end views, respectively, of the connector clamp.

In the construction shown, the connector comprises a terminal-engaging clamp 10 and a sleeve 11. The clamp 10 may be made of copper or other good conducting material and is formed 35 with a substantially circular portion 12 and jaws 13 integral therewith and extending in parallelism therefrom. The portion 12 of the member 10 has a tapered concentric bore 14, the diameter of which is slightly smaller than that of the standard storage battery terminal. The jaws 13 are semicircular in cross-section and the adjacent inner surfaces thereof are recessed, as at 15, for a purpose to be hereinafter described. The inner surface of sleeve 11 is slightly tapered and the outer surfaces of jaws 13 are correspondingly tapered, as is clearly illustrated in Fig. 1.

50 Numeral 16 designates an insulated cable from

the end of which the insulation has been removed, exposing ends 17 of conducting wires 18. A sleeve or cap 19 is formed around the exposed portions 17 of the wires by inserting said portions in a mold, pouring molten lead therein, and allowing 5 the lead to cool. A good electrical connection between the cap and the conducting wires 18 is thus secured.

In assembling the parts of my connector, the terminal clamp 10 is first placed over a battery 10 terminal, indicated by the numeral 20. As the diameter of the bore 14 is slightly smaller than that of terminal 20, the clamp, due to its resiliency, will tend to hug the terminal tightly. The capped end portion of conductor 16 is inserted into the space provided between jaws 13 by recesses 15, and the connection is completed by forcing the sleeve 11 on jaw 13 until it occupies the position shown in Fig. 1. The camming effect of the tapered inner surface of sleeve 11 20 upon the correspondingly tapered outer surfaces of jaws 13 will cause the jaws to grasp firmly the cap 19, and will clamp the circular portion 12 25 securely to the terminal post 20. The connector may be removed by sliding the sleeve 11 free from 30 jaws 13.

A good electrical connection between cap 19 and jaws 13 is assured, as the outer diameter of the cap is fixed by the size of the mold and is independent of the diameter of conductor 16. 35

In the above description I have illustrated one form of my invention. I am aware that various details of construction may be modified. I therefore do not intend to limit the patent granted to the form shown, but intend it to cover all modifications falling within the scope of the appended claim. 35

What I claim as new and desire to secure by Letters Patent of the United States, is—

A storage battery terminal connector comprising 40 a member having an eye for receiving a battery terminal post, a pair of jaws of semi-circular cross-section integral with said member, the adjacent surfaces of said jaws being recessed to accommodate a cable and the outer surfaces thereof 45 being tapered, a sleeve adapted for longitudinal sliding movement over a portion of said tapered surfaces, the inner surface of said sleeve being tapered whereby movement of said sleeve in one direction will cause said jaws to move toward each 50 other into holding engagement with said cable, thereby causing said member to be clamped to the battery terminal post and movement of said sleeve in the opposite direction will release said jaws and said clamping member. 55
